UNITED STATES PATENT OFFICE.

ALEXANDER BURKHARDT, OF INDIANAPOLIS, INDIANA.

ENGINE.

1,149,335.

Specification of Letters Patent. Patented Aug. 10, 1915.

Original application filed January 31, 1912, Serial No. 674,506. Divided and this application filed June 30, 1913, Serial No. 776,587.

To all whom it may concern:

Be it known that I, ALEXANDER BURKHARDT, a citizen of the United States, residing at Indianapolis, in the county of Marion and State of Indiana, have invented a new and useful Engine, of which the following is a specification, reference being had to the accompanying drawings and to the letters and figures of reference marked thereon.

This invention relates to stationary engines, more especially to engines that may be adapted to use steam, compressed air or explosive mixture as the motive force, the invention having reference more particularly to controlling valves for the motive fluid and to gearing or apparatus for operating and controlling the valves.

An object of the invention is to provide an improved engine of such construction as to be adapted to be variously modified for various uses, and especially adapted to be constructed in small sizes, another object being to provide improved explosive engine valves and operating mechanism therefor.

The invention comprises certain novel features of construction with respect to valve gearing and correlated elements of engines, and novel parts and combinations and arrangements of parts as hereinafter particularly described and further pointed out in the appended claims.

Referring to the drawings, Figure 1 is an elevation of the improved engine in its most simple form; Fig. 2, a top plan thereof; Fig. 3, a horizontal section approximately on the line A-A' in Fig. 1; Fig. 4, a plan of one of the main exhaust valves of the engine; Fig. 5, a fragmentary vertical section approximately on the line B-B' in Fig. 1; Fig. 6, a vertical section approximately on the line C-C' in Fig. 2; Fig. 7, a perspective view of one of the parts of the valve mechanism; Fig. 8, a fragmentary vertical section also on the line C-C' on an enlarged scale; Fig. 9, a fragmentary vertical section approximately on the line D-D' in Fig. 1; and Fig. 10, a fragmentary horizontal section on the line E-E' in Fig. 5.

In the different figures of the drawings like reference characters indicate like ele-

ments or features of construction herein referred to.

A suitable main frame is provided which preferably is composed of two similar base sections 1 and 1' and two top sections 2 and 3, all the sections being suitably bolted together. The top sections have outwardly extending shelf portions 4 and 5 respectively and constitute portions of the top of the frame which is designed to form a flat table upon which a suitable number of cylinders are secured in upright position, the frame as illustrated being designed to accommodate two cylinders 6 and 6' of identical construction which are secured upon the table, being partially upon the shelf portions thereof, the lower ends of the cylinders being open, the table having suitable openings therein corresponding to the bores 70 of the cylinders. The two cylinders have cylindrical exhaust boxes 7 and 7' thereon respectively that are preferably cast integrally with the cylinders, the cylinders having upper heads 8 and 8' respectively; the valve boxes having heads 9 and 9' respectively.

The main frame illustrated is a modification of the frame described and claimed in my pending application for Letters Patent, filed January 31, 1912, Serial No. 674,506, of which this is a divisional application for Letters Patent. The frame and the gearing therein will therefore be only briefly referred to.

For the purposes of the present invention the main frame is suitably bored out and has two large bushings 10 and 10' inserted and secured therein, and two journal boxes 11 and 11' are secured in the two bushings respectively. Two other bushings 12 and 12' which serve as journal boxes are secured also in the frame adjacent to the bushings 10 and 10'. A main shaft 13 is rotatably mounted in the journal boxes 11 and 11', and two crank wheels 14 and 14' are secured to opposite end portions of the main shaft and are provided respectively with crank pins 15 and 15'. A pitman 16 is connected to the crank pin 15, another pitman 16' being connected to the crank pin 15'. The two cylinders 6 and 6' have pistons 17 and

17' therein respectively, the pistons being connected respectively to the pitmen 16 and 16'. A toothed gear wheel 18 is fixedly secured to the main shaft 13 between the 5 journal boxes 11 and 11'. A counter-shaft 19 is rotatably mounted in the journal boxes 12 and 12' and has a pinion or gear wheel 20 of suitable diameter secured thereto, that is in mesh with the wheel 18, the counter-shaft extending outward beyond one of the 10 journal boxes for transmitting power. Two casing plates 21 and 22 are secured to opposite sides of the main frame and have offset portions 23 and 24 respectively that conform 15 to the shelf portions 4 and 5.

The two cylinders 6 and 6', illustrated as being sufficient for an understanding of the invention, have fuel supply boxes 25 and 25' upon their respective heads, the heads having bushings 26 and 26' therein respectively, and inlet valves 27 and 27' are seated in the lower ends of the bushings so as to open inwardly into the cylinders, the valves being provided with controlling stems 28 and 28' respectively which are guided in heads 29 and 29' removably inserted in the upper portions of the walls of the supply boxes, the heads being suitably recessed in their outer sides, and a spring 30 is seated in each 30 recess and has contact with a pin 31 secured in the stem. The stems and the springs are covered by means of caps 32 and 32' removably connected to the two heads respectively. The valves may be opened either by suction 35 of the engine pistons or by means of fluid pressure in the supply box and are closed, when not forced open, by means of the springs. The exhaust valve boxes 7 and 7' extend from the lower ends of the cylinders 40 upward to the plane of the cylinder heads. The heads 9 and 9' of the valve boxes have cylindrical valve chests 33 and 33' thereon respectively, the bore of each valve chest extending through the head, and the ends of 45 the valve chests have removable caps 34 and 34' thereon in which are vent holes 35 and 35'. The valve chests have ports 36 and 36' in the walls thereof extending from the ports of the chests to the interior of the adjacent fuel supply boxes. The wall of each 50 exhaust valve box has a vent hole 37 therein adjacent to the head of the box. Each valve chest has an inlet port 38 therein that is opposite to the port 33 or 33' and has a supply pipe 39 or 39' connected therewith through which to conduct explosive mixture, compressed air, or suitable fluid as a medium for producing power to actuate the pistons of the engine. The two cylinders have main 55 exhaust ports 40 and 40' respectively that extend through the walls of the cylinders to the adjacent exhaust valve boxes, the position of each port being near the lower end of the cylinder so that it shall be opened 60 when the piston descends to the end of the

cylinder on its downward stroke, the upper portions of the cylinders being provided respectively with auxiliary exhaust ports 41 and 41' that are relatively near the cylinder heads and afford communication between 70 the cylinders and the exhaust valve boxes. The wall of each exhaust valve box has an outlet opening 42 therein, and preferably two exhaust pipes 43 and 43' are connected with the outlet openings of the two boxes 75 and also with a relatively larger discharge pipe 44.

The two exhaust valve boxes 7 and 7' have annular main exhaust valves 45 and 45' therein that are adapted to close the exhaust ports 40 and 40' respectively, but are employed more particularly for another purpose which will further appear, the valves being of cylindrical or piston form and having central openings 46 and 46' therein respectively. Cylindrical auxiliary exhaust valves 47 and 47' are movably arranged in the upper portion of the exhaust valve boxes and have downwardly extending truncated extensions 48 and 48' thereon having smooth bores 49 and 49' respectively that extend through the valves. Two connecting rods 50 and 50' are suitably secured to each exhaust valve 45 or 45' and also to the opposite auxiliary exhaust valve 47 or 47', the rods being of the required length so as to move the auxiliary exhaust valve and close the auxiliary exhaust port when the main exhaust valve closes the main exhaust port.

Check valves 51 and 51' are normally seated upon the main exhaust valves 45 and 45' so as to close the openings therein respectively, and are guided on the rods 50 and 50' so as to move away from the valves until stopped by collars 52 and 52' secured to the rods, the check valves being adapted to prevent exhaust gases from passing down through the main exhaust valves and main exhaust ports and through the cylinders to the atmosphere when the pistons are above 110 the main exhaust ports. Two connecting rods 53 and 53' are secured to each main exhaust valve, as 45, and extend downwardly and are secured to a cylindrical head 54 or 54' that is movable in the lower portion of the exhaust valve box to prevent the exhaust gases from escaping out of the exhaust valve box, the movable heads having cylindrical truncated extensions 55 and 55' respectively which serve as packing boxes and that have 115 smooth bores 56 and 56' therein that extend through the heads. Each of said heads have two rods 57 and 57' secured thereto on opposite sides of the truncated extensions for operating and controlling the heads and valves connected therewith. Two bracket heads 58 and 58' are suitably secured to the main frame and have guide arms 59 and 59' and also guide arms 60 and 60' respectively through which the rods 57 and 57' movably 120

125 130 135

extend, the lower portions of the rods having enlarged extensions constituting plungers 61 and 61' that are directly guided in the arms 59 or 59'. The plungers have collars 62 and 62' thereon respectively on which springs 63 and 63' are seated, the springs being under compression in contact with the guide arm 60 or 60' for projecting the plungers downward. Valve rods 64 and 64' are guided in the arms 59 and 59' and extend upward through the movable heads and also through the main exhaust valves and the check valves thereon, thence upward through the auxiliary exhaust valves 15 and their packing boxes and thence into the valve chests 33 and 33' respectively, and have piston shaped valves 65 and 65' secured thereto respectively that are adapted to normally close the ports 36 and 36' and also the 20 opposite ports 38. Piston heads 66 and 66' are secured to the rods a suitable distance below the valves, so as to prevent fluid from escaping into the exhaust valve boxes when the inlet valves open the ports 38, the pistons being fitted movably in the bores of the 25 valve chest. The rods 64 and 64' have also piston heads 67 and 67' secured thereto respectively that are movably fitted in the bores 49 and 49' to prevent the exhaust 30 gases from escaping through the auxiliary exhaust valves, said rods having also piston heads 68 and 68' thereon respectively that are movably fitted in the bores 56 and 56' to prevent the exhaust gases from escaping 35 through the movable heads 54 and 54' respectively.

It should be understood that the piston heads in the exhaust valves and movable heads serve the purpose of packings in the 40 openings through which the rods 64 and 64' operate, and that any other suitable means for the purpose may be substituted therefor if preferred. The lower ends of the rods 64 and 64' have plungers 69 and 69' thereon 45 respectively that are movably guided in the guide arm 59 or 59' between the plungers 61 and 61', and are provided with fixed collars 70 and 70' respectively on which springs 71 and 71' are seated respectively, the springs 50 being under compression in contact with the arms 60 and 60' respectively for normally holding the valves 65 and 65' in closed position.

The two crank wheels or disks 14 and 14' 55 are provided on their inner sides with cylindrical guides 72 and 72' respectively on which the plungers of the valve rods may be supported or stopped in their downward movement, the plungers, however, being preferably held slightly away from the guides by means of their collars and the lower guide arms 59 and 59'. The guides 60 72 and 72' have short cams 73 and 73' thereon respectively that extend circumferentially, the cams being so placed as to be

moved under and lift the plungers 69 and 69' at the proper periods for opening the valves 65 and 65' respectively, and also to permit the plungers to descend for closing the valves at the proper period to correspond with the movement of the pistons in the cylinders. The guides 72 and 72' have also relatively longer circumferentially extending cams 74 and 74' thereon respectively that are movable periodically under the 75 plungers 61 and 61' respectively for opening the exhaust valves.

It should be understood that any suitable number of cylinders may be employed and the pistons thereof operatively connected together in various arrangements, and various modifications or equivalent construction may fairly be made within the scope of the accompanying claims.

In practical use explosive charges are admitted to the upper ends of the cylinders while the pistons are passing toward the cylinder heads, the charges being forced into the cylinders and exploded under compression. When the pistons are forced 90 downwardly by the explosions until the main exhaust ports are opened, the exhaust valves are moved so as to also open the main exhaust port and the auxiliary exhaust port, the exhaust gases passing out through the 95 discharge opening 42 as indicated by arrows in Fig. 8, the check valves being lifted to open the passage through the main exhaust valve. While the pistons are moving upward the cylinder is scavenged by the residue 100 due of the gases passing out through the auxiliary exhaust port 41 or 41' until closed by the auxiliary valve 47 or 47', after which the charging and explosions are continued. The obvious results of the operation of the 105 engine will be readily understood from the description of the construction and function of the various parts thereof without further reference thereto in detail.

Having thus described the invention, what is claimed as new is—

1. An engine including a frame, a crank shaft rotatably mounted in the frame, a cylinder mounted uprightly upon the frame and having a cylindrical exhaust valve box 110 thereon provided with heads, the wall of the cylinder having two exhaust ports therein extending to the valve box, the wall of the box having an outlet opening therein on a plane between the two ports, two exhaust valves movable in the box to close the ports, one of the valves being annular, a rod connected to the two valves, a check valve guided in the box for temporarily closing the opening in the annular valve, a piston in the cylinder, and a pitman connected to the piston and the crank shaft.

2. An engine including a frame having two guides, a shaft rotatably mounted in the frame and provided with a disk and two

companion cams rotatable with the shaft, a crank pin secured to the disk, a cylinder mounted on the frame and having a cylindrical exhaust valve box thereon, the cylinder having a head on one end and also a fuel supply box provided with a valve to admit fuel to the cylinder, the wall of the cylinder having a main exhaust port and also an auxiliary exhaust port therein extending to the valve box, an annular main exhaust valve and an auxiliary exhaust valve movable in the exhaust valve box, two rods connected to the main and auxiliary exhaust valves, a check valve movably mounted on the rods to close or open the opening of the annular main valve, two rods connected to the main exhaust valve and having plungers thereon in the path of the two cams respectively, the plungers being guided respectively in the two guides, a piston movable in the cylinder, and a pitman connected to the piston and the crank pin.

3. An engine including a frame, a shaft rotatably mounted in the frame, a disk fixed on the shaft and having thereon two companion cams and also a relatively shorter cam, the shorter cam being between the planes of movement of the two cams, a crank-pin secured to the disk, a cylinder mounted on the frame and having a cylindrical exhaust valve box and also a valve chest thereon, the cylinder having a head on one end and an inlet valve between the cylinder and the chest, the wall of the cylinder having a main exhaust port and also an auxiliary exhaust port therein extending to the exhaust valve box, a main exhaust valve and an auxiliary exhaust valve movable in the exhaust valve box, an inlet valve movable in the valve chest, two rods connected to the main and auxiliary exhaust valves, two rods connected to the main exhaust valve and having plungers thereon in the path of the companion cams, and a rod connected to the inlet valve and extending through the main and auxiliary exhaust valves and having a plunger thereon in the path of the shorter cam.

4. An engine including a frame having a plurality of guides, a shaft rotatably mounted in the frame, a disk fixed on the shaft and having thereon two companion cams and also a relatively shorter cam, the shorter cam being between the planes of movement of the two cams, a crank pin secured to the disk, a cylinder mounted on the frame and having a cylindrical exhaust valve box and also a valve chest thereon, the cylinder having a head on one end provided with a fuel supply box that is in communication with the valve chest, the wall of the cylinder having a main exhaust port and also an auxiliary exhaust port therein extending to the exhaust valve box, a valve for opening or closing communication between the fuel sup-

ply box and the cylinder, a main exhaust valve and an auxiliary exhaust valve movable in the exhaust valve box, an inlet valve movable in the valve chest, two rods connected to the main and auxiliary exhaust valves, two rods connected to the main exhaust valve and having plungers thereon in the path of the companion cams, and a rod connected to the inlet valve and extending through the main and auxiliary exhaust valves and having a plunger thereon in the path of the shorter cam, said plungers being guided by said guides respectively, and a piston in the cylinder and operatively connected with the crank pin.

5. In an engine, the combination of a cylindrical exhaust valve box that is open at one end, the opposite end having a fixed head, the wall of the box having two exhaust ports therein, a valve chest on said head, an inlet valve movable in the valve chest, a head movable in the open end portion of the box, two annular exhaust valves movable in the box, rods connected to the two exhaust valves, two rods connected to one of the exhaust valves and extending through the movable head, and a rod connected to the inlet valve and extending through the two exhaust valves and the movable head.

6. In an engine, the combination of a cylindrical exhaust valve box having an exhaust port in its wall, one end of the box having a head thereon, a ported valve chest on the head having a bore extending through the head, an inlet valve movable in the bore, an exhaust valve movable in the box at the exhaust port and having an extension thereon, the valve and the extension having a bore extending therethrough, two operating-rods secured to the exhaust valve, and a single operating-rod secured to the inlet valve and having a piston thereon that is movable in the bore of the valve chest and the head, the single operating-rod extending between the two operating-rods and having a piston thereon that is movable in the bore of the exhaust valve and its extension.

7. In an engine, the combination of a cylindrical exhaust valve box that is open at one end, the opposite end having a fixed head, the wall of the box having an outlet-opening and two exhaust ports therein and a vent at said head, a valve chest on said head having a bore extending through the head, an inlet valve movable in the valve chest, a head movable in the open end portion of the box and having a bore therein, an annular exhaust valve movable in the box at one of the two exhaust ports, an auxiliary exhaust valve movable in the box between the remaining one of the ports and the vent, said auxiliary valve having a bore therein, two rods secured to the annular exhaust valve and to the auxiliary valve, a check valve guided on the rods to open or close

the opening in the annular exhaust valve, two rods secured to the annular valve and the movable head, and an operating-rod secured to the inlet valve and extending 5 through the auxiliary valve and the annular valve and also through the check valve and the movable head, said rod having fixed thereon a piston movable in the bore of the valve chest and a piston movable in the bore

of the auxiliary valve and also a piston 10 movable in the bore of the movable head.

In testimony whereof I affix my signature in presence of two witnesses.

ALEXANDER BURKHARDT.
